ELECTRIC DISCHARGE DEVICE

William R. Baker, Berkeley, Calif., assignor to the
United States of America as represented by the
United States Atomic Energy Commission

Application July 26, 1949, Serial No. 106,913

22 Claims. (Cl. 250—27.5)

1

This invention relates to electric discharge devices in general, and more particularly relates to improvements in hot cathode gaseous discharge devices.

Recent advances in the fields of electric power and communication have created the need for switch gear capable of handling large amounts of power. It has been found that electric discharge devices are highly efficient and satisfactory for this purpose when only nominal amounts of power are involved. However, attempts to increase the power rating of such devices to any appreciable extent by enlarging the physical proportions thereof have proven inadequate and unsatisfactory, since, in general, a large increase in power rating is obtainable only at the expense of reducing the life of the apparatus. While electric discharge devices having ratings of the order of three kilowatts of continuous power and two to three megawatts of pulsed power have been developed, even these seemingly large power ratings have proven grossly insufficient for the demands of industry. Inherent limitation in conventional structure resulting from maximum possible size of cathode-emitting surface, extensive insulation requirements, and complicated grid construction have, prior to the present invention, served to prevent the necessary increase in power rating of conventional gaseous electric discharge devices. Various other types of devices, such as for example spark gaps, have been utilized in this connection; however, none has proven capable of satisfying the desired requirements, such as for example high power rating, variable voltage characteristics, precise control of ignition time, and small size.

It is therefore an object of the present invention to provide a new and improved heavy duty gaseous electric discharge device of relatively small size capable of passing greatly increased amounts of continuous power.

It is another object of this invention to provide a new and improved heavy duty electric discharge apparatus of relatively small size capable of passing greatly increased amounts of pulsed power.

It is another object of this invention to provide a relatively small electric discharge device of relatively very large power rating having variable voltage characteristics.

It is a further object of this invention to pro-

2

vide such an electric discharge device having the characteristic of precisely controllable ignition time.

It is yet a further object of this invention to provide a relatively small electric discharge device capable of passing thousands of amperes of pulsed current.

Another object is to provide a new and improved cathode construction for use in combination with electric discharge apparatus adapted for heavy-duty usage.

A still further object of this invention is to provide an electric discharge device capable of withstanding reversal of plate voltage within a short time of firing.

The manner in which the above objects are realized may be best understood by reference to the following description and accompanying drawing in which Figure 1 is a longitudinal sectional view of the device taken on the median plane; Fig. 2 is a plan view of the cathode; and Fig. 3 is a plan view of the grid structure.

With reference to the drawing, it is to be noted that in a preferred construction a cylindrical base unit 1 is provided to contain and support the cathode structure. This base unit 1 is preferably formed of a metal having a high coefficient of heat conductivity, such as copper.

Immediately above the base unit 1 there is situated a grid 2 supported by a ring 3 of insulating material. This ring 3 rests upon an annular projection 4 about the exterior of the base unit 1, and is adapted to slip fit about a shoulder 6 upon this annular projection thereby preventing lateral motion of the ring 3.

The grid structure 2 has the form of a cylinder of slightly larger diameter than the cylindrical base unit 1 and has a circumferential rim 7 formed on the inner diameter of the cylinder and projecting downward from a vertical wall thereof. In assembly of the device, the grid structure 2 rests upon the insulating ring 3 with the rim 7 in contact with the insulating ring 3 about the top inner circumference thereof, thereby preventing lateral motion of the grid 2 with respect to the insulating ring 3. With the grid structure 2, insulating ring 3, and base unit 1 assembled as set forth above, the base unit extends into the grid cylinder although not in contact therewith and thus entirely masks the insulating ring 3.

from the interior of the base unit as illustrated in Fig. 1. The insulator ring 3 is thereby shielded from heat radiation by the cathode and also from stray electrons.

The grid structure 2 has a double-stepped portion formed about the top of the outer periphery whereby two horizontal annular levels are provided thereabout. A second insulating ring 8 rests upon the lower of these annular levels and abuts the vertical portion of the first step, and is separated from the top of the grid structure by the width of the top annular level. As the inner diameter of the ring 8 is substantially the same as the diameter of the vertical portion of the lower step, the ring 8 is restrained from any lateral motion with respect to the grid structure 2 when assembled therewith.

Atop the grid structure 2 and adjacent thereto is situated the anode 11 which is spaced from the grid 2 by the insulating ring 8. The anode 11 is also cylindrical, preferably formed of a metal having good heat conductivity, and like the grid 2 has three different outer diameters joined by two annular levels; however, unlike the grid 2, the smallest diameter of the anode 11 is the lowest, thus producing an inverted step periphery. The anode 11 is supported by the ring 8, the top of which is in contact with the outer annular level of the anode, and the anode is secured from lateral motion by circumferential contact between the inner periphery of the ring 8 and the vertical portion separating the two annular levels on the anode 11.

As has been noted above, a metal having a high coefficient of heat transfer, such as copper, may be advantageously employed as the material from which the anode, grid, and base unit are formed. It is to be further noted in this respect that the use of a metal having a small amount of occluded gases such as oxygen-free copper is particularly desirable, as contamination of the atmosphere within the device is thereby minimized. Also when an atmosphere of hydrogen is used oxygen-free copper is preferable to regular copper which disintegrates in such an atmosphere.

The entire assembly set forth above is made gas-tight by the insertion of ring gaskets 12 between the insulator ring 3 and the base unit 1 and grid 2 and between the insulator ring 8 and the grid 2 and anode 11. The apparatus may be maintained in assembled position by means of clamps or other suitable mechanical means and may be surrounded by appropriate insulating material such as a glass cover; however, for certain applications it has been found advantageous to utilize only the effect of the low internal pressure to maintain the apparatus in assembled position and to forego the advantages of exterior insulation for the resulting ease of disassembly of the apparatus.

Within the base unit 1 there is situated an improved cup-shaped cathode 21 substantially concentric with the base unit. The cathode-emitting surface comprises a multiplicity of fins arranged longitudinally within the cathode cup, as illustrated in Fig. 2. These fins are attached to the inner surface of the cathode wall and extend radially inward from the wall. This particular embodiment utilizes three sets of fins of differing size, an illustrative example of each size of fin being numbered 22, 23, and 24 respectively in order of size from the largest to the smallest. Maximum cathode emission is limited in part by the area of cathode-emitting surface, and thus it is advantageous to provide as large a surface as

is possible and feasible without increasing the over-all size of a unit. The cathode-emitting surface may be advantageously increased by the use of fins as is done in the present invention; however, the number and size of fins that may be advantageously employed is limited by space charge considerations. When the dimension of the radial fin depth is less than that of fin separation, blocking of the passage between fins occurs as a result of space charge and other effects with a resultant nullification of the advantages of increased size of cathode-emitting surface. The present invention overcomes this limitation by utilizing a novel and particularly advantageous arrangement of fins wherein the spacing between any fin and its largest neighboring fin is always substantially equal to the first-mentioned fin depth. Fins of three different sizes are utilized in the illustrated embodiment, the largest fins 22 having a radial depth of twice the radial depth of the intermediate fins 23 and four times the radial depth of the small fins 24. The fins are arranged so that a fin of intermediate depth is between and equidistant from two large fins, and a small fin is between and equidistant from a large fin and an intermediate fin. Thus the sequence of fins about the inner circumference of the cathode cup is large fin 22, small fin 24, intermediate fin 23, small fin 24, large fin 22, etc. The distance between adjacent large fins 22 is substantially equal to their radial depth, the distance between each fin 23 of intermediate depth and the adjacent large fin 22 is substantially equal to the radial depth of the intermediate fin 23 and the distance between the small fin 24 and the adjacent fin, either large or intermediate, is substantially equal to the radial depth of the small fin 24. If the radial depth of the largest fins be maintained substantially less than the radius of the cylinder, approximately $\frac{1}{4}$ the radius or less, then the radial depth of the fins will be substantially equal to their separation along the cathode cylinder. With the inner surface of the cylinder being electron emissive the utilization of one set of electron emissive fins in accordance with the above principles will substantially triple the cathode emission surface, two sets of fins will make substantially four times the emission surface and three sets of fins as illustrated will make substantially five times the cathode emission surface that would be available without the fins. Thus the use of any number of sets of straight fins in accordance with the principles of the invention, and under the circumstances set forth above will result in the cathode emission surface being equal to the area of the area of the surface upon which the fins are mounted multiplied by a factor of two plus the number of sets of fins. It is to be noted that the above increase in cathode emission surface is accomplished without the deleterious effects of space charge, and thus all of the surface is useful. It will of course be appreciated that the cathode may have any of a variety of configurations other than that of the hollow cylinder illustrated and also that there is no limitation upon the number of sets of fins that may be utilized. It may be further noted that fins of other shape or configuration may be utilized; however, in such case the above-noted relationship between the cathode emission surface with and without fins must of course be altered to fit the circumstances. The cathode-emission surface of the present invention is preferably either oxide-coated or formed of a suitable cathode material, and in-

direct heating is utilized to make this surface electron-emissive. In order to properly utilize the large cathode-emission surface, it is of importance that a large amount of heat be available. Heat in the necessary quantity is provided in the illustrated embodiment by a heater unit 31 which is coiled about the exterior of the cathode cup 21 and is substantially in contact therewith. This heater unit may be advantageously composed of a stainless steel sheath 32 having a chrome nickel heating wire 34 passing through the center of the sheath 32 and insulating material 33 such as magnesium oxide, within the sheath 32 and about the heater wire 34, thereby preventing electrical contact between the heater wire 34 and sheath 32 over the length of both. One end of the sheath 32 is closed and the heater wire 34 is electrically connected to the sheath at this end, the other end of the sheath being open with the wire extending therefrom. In assembly, the closed end of the heating unit 31 is positioned at the top of the cathode cup 21 and the heating unit 31 wound about the exterior of the cathode cup from top to bottom. The open end of the heating unit is extended through the bottom of the base unit 1 and the sheath is secured to the base unit by suitable means such as brazing. A grounded source of heating current is connected to the heater wire 34 exterior to the discharge device whereby a heating current flows through the heating wire 34 to the closed end of the sheath 32 and thence through the sheath to the grounded base unit. It is to be noted that numerous advantages accrue from the use of this type of heater unit. First a very large amount of heat is available without danger of burning out the heater unit, secondly the heater unit has a very long life, and thirdly the problem of sealing the heating unit leads is minimized.

Provision is made to fully utilize the heat available from the cathode heater 31 by supplying a heat shield 26 which is located within the base unit 1 about the cathode cup 21 and heater unit 31. The heat shield depicted in Fig. 1 is formed of multiple layers of stainless steel spaced apart and situated about the inside of the base unit 1. The inner surfaces of these layers are polished in order to reflect heat toward the center of the base unit 1. It will of course be appreciated that innumerable types of heat shields could be utilized in this connection and that the one shown and described is only presented by way of illustration.

The grid structure 2 as illustrated in Figs. 1 and 3 is relatively deep in a vertical dimension and has vertical slots 41 formed therein. These slots may be formed directly in the grid 2 or as illustrated a slot structure comprising equivalent bars 42 defining equivalent slots 41 may be inserted in a composite grid structure. This slot structure may be advantageously formed of a durable material such as tungsten.

Considering the grid structure it is to be noted that the discharge device of the present invention preferably has a voltage rating of the order of tens of thousands of volts and that the grid must be capable of preventing electrical breakdown between the anode and cathode at these voltages. In this respect the depth-to-width ratio of the grid slots is of importance, and it has been found to be advisable with this order of magnitude of voltage rating to limit straight grid slots to a depth-to-width ratio of 3 to 1 or more in order to prevent electrical breakdown between the anode and cathode as a result of the voltage

differential existing therebetween, and also to limit the slot width to approximately the same dimension as the anode-grid spacing in order to preclude undesirable ionization. With such a ratio, the anode is adequately electrically masked from the cathode to prevent a sufficient number of electrons from passing into the grid-anode region to ionize the gas therein. It will of course be appreciated that the grid slots could be other than straight as depicted and that in such case the grid slot depth-to-width ratio could be reduced. However, in the interest of minimizing the length of the electron path from the cathode to anode for reasons set forth below, it has been found advantageous to utilize straight grid slots with the required depth-to-width ratio.

It will be appreciated that the problems of insulation in the present device are of appreciable magnitude. In order to overcome these problems the grid-anode spacing is maintained less than the mean-free path of electrons in hydrogen at the pressure inside the device, thereby substantially eliminating the possibility of ionization in this space by stray electrons. Also, all of the metal-insulator contacts are in field-free regions, thus preventing electrical breakdown across the insulators.

The base unit 1, grid structure 2, and anode 11 may be cooled by means of water flowing through pipes secured about these units as illustrated. All of the above elements are formed of metal having a high coefficient of heat conductivity and thus very large amounts of heat may be dissipated within the device without damage to the elements thereof as the heat rapidly passes through the elements and may be carried away by the cooling water.

The improved electric discharge device of the present invention is sealed gas-tight as noted above and is filled with an ionizable atmosphere at low pressure. The embodiment illustrated utilizes hydrogen which is circulated through connections 51 and 52. In connection with the hydrogen circulation, there may be utilized a hydrogen filter, regulator, and valve (not shown) of a type well known in the art. The hydrogen atmosphere is maintained at a few hundred microns pressure which may be varied considerably without materially affecting the operation or characteristics of the device. It will of course be appreciated that a sealed system may be utilized instead of the circulating hydrogen system depicted and described above and in such case it is advantageous to utilize a gas reservoir within the device. Also many different types of atmospheres may be utilized; however, advantage lies in employing a gas having a low atomic number, as the deionization time is thereby minimized, and it is necessary to employ an atmosphere which will not deleteriously affect the cathode emission surface.

In operation, the anode is maintained at a positive potential relative to the base unit and cathode which may be advantageously grounded. In this respect it may be noted that the apparatus satisfactorily operates with an anode voltage of 20,000 volts. With the base unit 1 grounded the heater wire 34 is connected to a source of electric current which utilizes a ground return through the base unit via the connection between the heater and base unit 1. With the heater unit energized and a high positive potential applied to the anode 11, the grid electrically masks the cathode from the anode so that an insufficient number of elec-

trons enter the anode-grid space to ionize the gas therein and cause electrical breakdown. This masking effect is a result of the grid structure and not because of any particular potential impressed thereon.

Electric discharge is initiated by a positive trigger voltage applied to the grid 2 by any suitable means (not shown). This positive voltage pulse applied to the grid 2 causes electrons to be attracted to the grid. A large amount of electrons is available at the cathode as a consequence of the oversized cathode-emitting surface and the application of a positive trigger voltage to the grid attracts a large quantity of electrons from the cathode toward the grid. These electrons subsequently pass through the grid slots 41 into the anode-grid space, ionizing the gas therein and causing electrical breakdown and discharge of the device. A suitable load (not shown) is connected between the anode and the cathode, thus providing a return path for the electric discharge.

It is to be noted at this point that electrons traveling from the cathode to anode are not constrained to negotiate tortuous paths as is customary in conventional gaseous electric discharge devices known in the art. To the contrary, the electron path from the cathode contains only a slight bend in order to pass directly through the grid slots to the anode.

Great difficulty has heretofore been encountered in firing discharge devices precisely with regard to time. In practical terms this may be stated as a variation between cycles of trigger voltage of the time that discharge is initiated in the discharge device. This phenomenon is depicted on an oscilloscope screen as a waver or "jitter" of the discharge line and is thus generally referred to as jitter time. Thus the term jitter time as employed herein is taken to mean the variation of the voltage necessary to initiate discharge of the device, expressed as time. It will of course be apparent that the time voltage relationship is obtained from the trigger voltage wave form.

As noted above, the minimizing of jitter time is highly advantageous. The present invention decreases jitter time to a remarkable degree. This is strikingly apparent when considered in the light of the power rating of the device. Owing in part to the oversized cathode-emission surface and in part to the novel grid construction and placement, the present discharge device is capable of operating with a jitter time of less than 0.05 microsecond.

Another important consideration is the ability of the device to withstand rapid reversals of plate voltage. The repetition rate of conventional discharge devices is limited by the tendency for electrical breakdown to occur between the anode and grid, such breakdown commonly occurring between the leads to these elements with consequent destruction of the glass seal therebetween; however, this limitation is not present in this invention as the construction of the device precludes electrical breakdown at any place except directly between the anode and grid which is of no consequence owing to the rugged structure of these elements.

The present invention has been disclosed in only one particular embodiment; however, it will be apparent to those skilled in the art that numerous modifications and variations are possible within the spirit and scope of the invention and thus it is not intended to limit the invention to

the details shown except as defined in the following claims.

What is claimed is:

1. A gaseous discharge device comprising a cathode, an anode at a positive potential with respect thereto, an ionizable atmosphere therebetween, and a grid having transverse openings therethrough positioned between said anode and cathode, said grid being electrically insulated from said anode and cathode and being separated from said anode by less than the mean-free path of electrons in said atmosphere, the openings in said grid having a depth-to-width ratio of approximately three to one, whereby said cathode is electrically masked from said anode, said grid being adapted to receive a pulse of positive voltage whereby the masking action of said grid is overcome.
2. A gaseous discharge device comprising a cathode, an anode at a positive potential with respect thereto, an atmosphere of low pressure hydrogen therebetween, a control electrode disposed between said anode and cathode and parallel to said anode, said electrode having transverse openings therethrough and being separated from said anode by less than the mean-free path of electrons in said atmosphere, the transverse openings in said control electrode having a depth-to-width ratio of approximately three to one, whereby said cathode is electrically masked from said anode.
3. In a gaseous discharge device, the combination comprising a cathode, an anode at a high potential with respect thereto, a low pressure ionizable atmosphere therebetween, a grid parallel to said anode between said anode and cathode and electrically insulated therefrom, said grid being separated from said anode by less than the mean-free path of electrons in said atmosphere, said grid having transverse openings therethrough of a depth-to-width ratio of approximately three to one, whereby said cathode is electrically masked from said anode.
4. In a gaseous discharge device, the combination comprising an anode, a cathode, and a control electrode disposed therebetween, a low pressure hydrogen atmosphere between said anode, cathode, and control electrode, and said anode and control electrode being formed of oxygen-free copper, whereby said anode and control electrode have the property of good electrical and thermal conductivity without suffering destruction by said atmosphere.
5. A gaseous discharge device comprising a cathode at substantially ground potential, an anode at a positive potential, an ionizable atmosphere therebetween, and a control electrode disposed between said anode and cathode and insulated therefrom whereby the potential thereof is electrostatically determined, said electrode having transverse apertures therein for the passage of electric discharge therethrough, said apertures having a depth-to-width ratio in excess of three to one, whereby discharge of said device is prevented, said grid being adapted to receive a positive voltage pulse, whereby said device discharges.
6. In a gaseous discharge device the combination comprising an anode and a cathode in close proximity and having a large potential difference therebetween, and a slotted grid interposed between said anode and cathode, said grid being parallel to said anode and adjacent thereto, and said grid slots having a depth-to-width ratio

of at least three to one, whereby said anode is electrically masked from said cathode.

7. In a gaseous discharge device, the combination comprising an anode and a grid disposed in parallel relationship in a low pressure ionizable atmosphere, said grid and anode being separated by a distance less than the mean-free path of electrons in said atmosphere at said low pressure and more than the maximum distance for field emission between the anode and grid.

8. A gaseous discharge device as set forth in claim 7 further characterized by said atmosphere being helium.

9. A gaseous discharge device as set forth in claim 7 further characterized by said atmosphere being hydrogen, and said anode and grid being composed of oxygen-free copper.

10. In a gaseous discharge device, the combination comprising a flat metallic anode, and a flat metallic grid parallel to said anode and separated therefrom by less than the mean-free path of electrons in the atmosphere therebetween, both said anode and said grid being formed of a metal having a high coefficient of heat conductivity and being provided with external means for dissipating heat, whereby inverse discharge therebetween causes no damage to the anode or the grid.

11. In a gaseous discharge device, the combination of a thick metallic element having an opening therethrough, and a tungsten grid situated within said opening and secured therein, said combination comprising a control electrode of said gaseous discharge device.

12. In a gaseous discharge device, a control electrode comprising a thick metallic element having a plurality of transverse openings therein for the passage of an electric discharge therethrough, said openings having a depth-to-width ratio of at least three to one.

13. In a gaseous discharge device, the combination comprising an anode and a grid adjacent thereto, said anode and said grid having large volumes and being formed of copper metal, whereby the removal of power dissipated internal to said device is facilitated.

14. A gaseous discharge device as set forth in claim 13 further characterized by said copper metal being oxygen-free copper metal.

15. A gaseous discharge device comprising the combination of a cathode-emission surface including a hollow cylinder having a plurality of sets of fins longitudinally disposed upon the inner wall thereof, each of said sets of fins being of a different radial depth and being arranged with the circumferential distance between adjacent fins at least equal to the radial depth of the smaller, an anode disposed adjacent an open end of said cylinder, and a grid having slots of large depth-to-width ratio therein for the passage of electric discharge therethrough interposed between said anode and cathode, whereby said anode is electrically masked from said cathode with a potential of the order of twenty kilovolts therebetween.

16. In a gaseous discharge device, a cathode emission surface comprising a hollow cylinder having a number of sets of fins disposed about the inner wall thereof and parallel to the axis thereto, each of said sets of fins having twice the radial depth of the next smaller set, and said sets being arranged such that the spacing between adjacent fins is at least equal to the radial depth of the smaller of the two adjacent fins, whereby

the cathode emission surface is substantially free of blocking by space charge.

17. In a gaseous discharge device a cathode emission surface comprising a hollow cylinder having three sets of fins longitudinally disposed upon the inner wall thereof, the fins of the first set having twice the radial depth of the fins of the second set and four times the radial depth of the fins of the third set, there being twice as many fins in the third set as in the first and second sets, the fins of the first set being separated by a distance equal to the radial depth of one of these fins, and the sets of fins being arranged alternately with a fin of the second set 15 equidistant between two fins of the first set, and a fin of the third set equidistant between each adjacent fin of the first set and fin of the second set whereby the effective area of the cathode emission surface is substantially equal to five times the surface of the cylinder wall.

18. In a gaseous discharge device, the combination comprising a cathode having a cathode-emission surface thereon, said cathode including a wall and a number of sets of fins of varying size 25 secured thereto, said cathode-emission surface comprising said wall and said fins, and said sets of fins being symmetrically arranged upon said wall, whereby said cathode-emission surface is substantially equal to the area of said wall multiplied by a factor of two plus the number of sets of fins.

19. In a gaseous discharge device, the combination comprising a cathode having a cathode-emission surface and including a wall and a number of sets of fins, said cathode-emission surface comprising the surface of said wall and said sets of fins, the fins of each set having twice the radial depth of the fins of the next smaller set and said sets of fins being symmetrically disposed upon said wall with the spacing between adjacent fins being equal to the radial depth of the smaller, whereby the effective cathode emission surface is equal to the area of said wall multiplied by a factor of two plus the number of sets of fins, and a heater unit in close proximity with said cathode, said heater unit including a metal sheath closed at one end, a heater wire internal to said sheath and insulated therefrom, said heater wire and said sheath being electrically connected 40 at the closed end of said sheath, and said heater wire extending from the open end of said sheath, whereby an electric current path is provided through said heater wire and said sheath, said heater embracing said cathode, whereby said cathode is secured in position and heated by said heater.

20. A gaseous discharge device comprising a hollow cylindrical metal base unit, a cathode internal to said base unit, a heater unit about said cathode in contact therewith, said heater unit extending through a wall of said base unit and rigidly joined in metallic connection thereto, whereby said cathode is secured in position within said base unit.

21. In a gaseous discharge device a cathode heater comprising a metal sheath in the form of a tube closed at one end, a heater wire attached to the closed end of said sheath, passing through the center of said sheath and extending from the open end thereof, and insulating material filling said sheath about said heater wire whereby said heater wire is insulated from said sheath throughout its length.

22. A method of establishing an electric dis- 75 charge in an ionizable atmosphere comprising the

11

steps of establishing a potential differential in said ionizable atmosphere, producing a quantity of free electrons adjacent the negative end of said potential differential, establishing a region of substantially zero potential gradient, separating said free electrons from said potential differential by said region whereby said free electrons are electrically masked from said potential differential, and instantaneously imparting an appreciable unidirectional velocity to said free electrons toward said region of zero potential gradient causing said free electrons to pass therethrough into the influence of said potential differential, thereby ionizing said atmosphere and establishing an electric discharge.
